J. D. HENDRIX

DIRECTION SIGNAL LAMP FOR AUTOMOBILES

Filed July 18, 1923

FIG. 1.

FIG. 2.

UNITED STATES PATENT OFFICE.

JOHN D. HENDRIX, OF SEATTLE, WASHINGTON, ASSIGNOR TO OLIVER Z. PERRY, OF LOS ANGELES, CALIFORNIA.

DIRECTION-SIGNAL LAMP FOR AUTOMOBILES.

Application filed July 18, 1923. Serial No. 652,360.

To all whom it may concern:

Be it known that I, JOHN D. HENDRIX, a citizen of the United States of America, residing at Seattle, in the county of King and State of Washington, have invented certain new and useful Improvements in Direction-Signal Lamps for Automobiles, of which the following is a specification.

This invention relates to new and useful improvements in motor vehicle signal casings.

An important object of this invention is to provide a casing of a suitable design to furnish means for displaying a variety of warning signals to both the front and the rear of a vehicle.

A further object of the invention is to provide a signal casing that may be employed for the purpose of giving five different traffic signals, viz, slow speed ahead, stop, right and left turns, and parking.

A further object of the invention is to provide an improved construction for a signal casing which will permit quick assembly and disassembly of the various parts employed to form the same.

A further object of the invention is to provide a novel form of partition for a signal casing which consists of a comparatively few number of parts that are adapted for being separably connected to divide the casing into a desired number of separate compartments.

A further object of the invention is to provide improved means for mounting electric bulbs in the various compartments formed in the casing.

A still further object of the invention is the manner in which the various parts are assembled and retained in their respective positions for forming the complete signaling apparatus.

Other objects and advantages of the invention will be apparent during the course of the following description.

In the accompanying drawing forming a part of this specification and in which like numerals are employed to designate like parts throughout the same.

Figure 1 is an elevational view of the signal casing embodying this invention.

Figure 2 is a vertical sectional view taken through the signal casing shown in Fig. 1,

Figure 3 is a transverse sectional view

taken through the casing shown in Figs. 1 and 2,

Figure 4 is a side elevational view of one of the partitions employed for dividing the casing into a desired number of separate compartments,

Figure 5 is a side elevational view of the partition shown in Fig. 4, and

Figure 6 is a side elevational view of a locking member employed for performing the combined function of removably connecting a pair of the partitions shown in Figs. 4 and 5 and for further acting as partitioning means for coacting with the form of partition shown in Figs. 4 and 5 for further dividing the casing into compartments.

In the drawing, wherein for the purpose of illustration is shown a preferred embodiment of this invention, the numeral 7 designates a shallow cylindrical casing formed from any suitable metal and having outwardly directed annular flanges 8 that are formed integrally with the edges of the same. These outwardly directed flanges 8 are each provided with an inwardly extending annular flange 9, as best shown in Fig. 2. The cylindrical portion 7 of this casing is suitably connected to a pair of bracket arms 10 that are provided with angularly arranged feet 11 and are adapted for being employed to mount the casing 8 upon a convenient portion of an automobile. These bracket members are connected substantially intermediate their lengths by the bolt and nut 12.

For the purpose of dividing this casing into five compartments, four of which are illuminated, there are provided a series of partitions that are best illustrated in Figs. 3 to 6 inclusive. The form of partition shown in Figs. 4 and 5 is illustrated in Fig. 3 in duplicate and form what I will term side partitions 13 and 14. The partitions 13 and 14 are of identical construction with the exception of the arrangement of the means employed for supporting the electric sockets, it is believed, however, that for the present a description of the partition 13 shown in Figs. 4 and 5 will be sufficient for both.

This partition consists of an intermediate flat side portion 15 which is formed integrally at its upper and lower edges with the shoulder portions 16. The upper shoulder 16 is formed integrally with the offset

upper side portion 17 while the lower shoulder 16 is formed integrally with the offset lower side 18. The offset upper side 17 is formed integrally with the arcuate top portion 19 having at its outer edge an integrally formed depending end portion 20. The lower offset side 18 is provided with a relatively small arcuate end 21 that projects inwardly from the side 18. It will also be seen that the arcuate top 19 projects inwardly from the upper offset side 17. The intermediate flat side portion 15 and the shoulder portions 16 have the cutout portion 22 formed in one edge for a purpose 15 that will become apparent as the description proceeds.

It will be seen that the partitions 13 and 14 may be stamped from a sheet of metal and may be easily bent to form the 20 various portions just described. During the stamping of these partitions there are provided two openings 23 in each partition. These openings 23 are provided with four lugs 24 that are equally spaced around the 25 edge of the same and are bent inwardly, as illustrated in Figs. 3 and 4, for providing means for clamping the lamp sockets 25 in the manner illustrated in Fig. 3. It will be seen by examining this Fig. 3 that 30 the partition 13 is provided with an opening 23 in the upper portion of the intermediate flat side 15 and with a second opening 23 in the offset upper side 17. The partition 14 is provided with an aperture 35 23 in the upper portion of the intermediate flat side 15 and with a second aperture in the offset lower side 18. As has been previously stated, the positioning of these apertures 23 is the only difference in construction 40 between the partitions 13 and 14.

By referring to Fig. 6, it will be seen that there is provided a substantially U-shaped member 26 which I will term a partition key. This partition key consists 45 of an intermediate flat portion 27 that is formed integrally with the upper and lower walls 28 and 29 that extend laterally at right angles from the intermediate portion 27. This intermediate portion 27 is of less 50 width, for a portion of its length, than the width of the upper and lower walls 28 and 29.

By referring to Figs. 1 and 2, it will be seen that the casing 7 is provided with a 55 pair of end plates 30 that each consist of the annular rim portion 31 that is provided with an annular inwardly directed flange 32. Each of these rims 31 are provided with a diametrically extending cross piece 33, 60 having cut therein the oppositely directed arrow-shaped openings 34. The annular rims 31 and diametrically extending cross pieces 33 form the semi-circular openings 35 as shown in Fig. 1.

65 It is intended that the upper semi-circular

openings 35 will display green lights in both directions, or in other words to both the front and the rear of the casing. The arrow openings 34 are intended to display red lights from the rear of the casing and 70 green lights from the front of the casing. The semi-circular openings 35 formed in the lower half of the casing are intended to display a red light from the rear of the same and a frosted white light from the 75 front. For the purpose of displaying the different colored lights in the manner just described, I have provided a green lens 36 which covers a portion slightly less than one-half of the rear of the casing. The 80 remaining portion of the rear of the casing is provided with a red lens 37. It will be seen by this arrangement of lenses that the upper semi-circular opening 35 will display a green light, the arrow openings 34 will 85 display red lights, and the lower semi-circular opening 35 will display a red light. The front face of the casing is provided with a green lens 38 that covers a portion slightly greater than half of the opening 90 and that the remaining portion of the opening is provided with a frosted white lens 39. This arrangement will cause a green light to be displayed through the upper semi-circular opening 35, green lights to be 95 displayed through the arrow openings 34, and a white light to be displayed through the lower semi-circular opening 35.

The manner of assembling the various elements employed for forming this complete 100 signal casing is as follows:

The cylindrical casing or shell 7 is of course employed as the body portion of the entire apparatus. The lenses 38 and 39 are properly positioned within the front cover plate 30 and the same is then positioned against the outwardly directed annular shoulder 8 which is carried by the front side of the casing or shell 7. It is intended that the inwardly directed annular flange 9 carried by the flange 8 and the similarly formed flange 32 carried by the front end cover plate be provided with three equi-spaced openings with the openings formed in the flange 8 screw threaded. The screws 40 are then positioned within these three openings formed in each of the flanges 9 and 32 with the result that the front of the casing is entirely closed. The lenses 38 and 39 will be retained in their desired positions by the outwardly directed annular flange 8 carried by the cylindrical casing 7 and the annular rim 31 carried by the front cover plate 30. The side partitions 13 and 14 are next positioned within the cylindrical casing 7 in the manner illustrated in Fig. 3. It will be seen that the depending end portions 20 formed upon each of these partitions 13 and 14 will be positioned in abutting relation with each other and will be in 115 120 125 130

alinement with the upper screw 40 for the purpose of insuring the proper positioning of the said partitions in respect to the various openings 34 and 35 formed in the front 5 and rear cover plates. The partition key 26 is then inserted into the casing with the upper and lower walls 28 and 29 respectively positioned outwardly of the upper and lower shoulders 16 formed in the partitions 13 and 14. The cutaway portions 22 formed in the side partitions 13 and 14 will permit the intermediate portion 27 of the partition key 26 to be positioned with its outer face in vertical alinement with the 15 edges of the said side partitions. In other words the cutaway portions 22 allow for the counter-sinking of the intermediate portion 27 which forms a part of the partition key 26. It has been noted heretofore that the 20 intermediate portion 27 of this partition key is of less width, for a portion of its length, than the width of the upper and lower walls 28 and 29. The width of the intermediate portion 27 is intended to be equal to the distance 25 between the intermediate flat side portions 15 of the partitions 13 and 14. It will be seen that this partition key will act as a means for spreading the side partitions 13 and 14 for causing the relatively small arcuate lower end portions 21 to flushly engage the inner face of the cylindrical casing 7. This manner of interlocking the various partition members will cause the same to retain their desired respective positions while 30 they are within the casing. To complete the assembling of the signalling apparatus, colored lenses 36 and 37 are positioned within the rear cover plate 30 and the same is secured to the inwardly directed annular flanges 9 carried by the cylindrical casing 7 in the same manner described in connection with the front cover plate 30. The entire apparatus is then completely assembled.

In Figs. 2 and 5, there are shown apertures 41 that will allow for the passage of electric wires through the various partitions for connecting the different electric sockets 25 to a supply of current. These openings 41 may be positioned in any desired manner to permit the wiring of the said lamp socket. It is to be understood that the upper and lower compartments 42 and 43 respectively and the side compartments 44 and 45 will each be provided with an electric bulb 46 for illuminating the said compartments. Due to the fact that there has been provided green lenses on opposite sides of the compartment 42, green and red lenses on opposite sides of the compartments 44 and 45, and red and 50 frosted white lenses on opposite sides of the compartment 43, the electric bulbs 46 may be of a very low candle power and still comply with traffic regulations which usually call for the projecting of signal lights approximately two hundred feet.

As has been previously stated, this signal casing is adaptable for giving five different traffic signals. The upper semi-circular openings 35 which display green lights are appropriate for indicating a driver's intention to reduce his speed of travel. The oppositely directed arrow-shaped openings 34 will display green lights to the front of the casing and red lights to the rear. These arrows are intended to indicate the driver's intention of turning either to the right or left. The lower semi-circular openings 35 will display a red light to the rear of the casing and a white light to the front. These lower openings 35 are therefore suitable for indicating the driver's intention to stop his vehicle and may also be employed as a permanent parking light when the vehicle has been stopped for any considerable length of time.

It is to be understood that the form of this invention herewith shown and described is to be taken as the preferred example of the same, and that various changes in the shape, size, and arrangement of parts may be resorted to without departing from the spirit of the invention or the scope of the subjoined claims.

Having thus described the invention, I claim:—

1. In a signalling apparatus of the class described, a cylindrical casing having open ends, a series of interlocked partitions within said casing dividing the latter into a plurality of compartments, said partitions consisting of side sections for forming side compartments outwardly thereof adapted for bearing against the upper and lower inner faces of said casing and having offset central portions, and a central section interlocking with the offset portions of the side sections for forming upper and lower compartments above and below said section, illuminating means in each compartment, sectional lenses positioned within said open ends, and cover plates secured to the ends of said casing for holding said lenses in place.

2. In a signalling apparatus of the class described, a cylindrical casing having open ends, a series of interlocked partitions within said casing dividing the latter into a plurality of compartments, said partitions consisting of vertically extending side sections and having offset central portions and having inwardly directed arcuate end portions conforming in outline with and bearing against the upper and lower inner faces of said casing for forming side compartments, and a horizontally extending central section interlocking with the offset portions of the side sections for forming upper and lower compartments above and below said section, illuminating means in each compartment, sectional lenses positioned

within said open ends, and cover plates secured to the ends of said casing for holding said lenses in place.

3. In a signalling apparatus of the class described, a cylindrical casing having open ends, a series of interlocked partitions within said casing dividing the latter into a plurality of compartments, said partitions consisting of vertically extending side sections for forming side compartments outwardly thereof having inwardly directed arcuate end portions conforming in outline with and bearing against the upper and lower inner faces of said casing, inwardly directed spaced shoulders carried by the side sections, and a U-shaped central section engaging said shoulders for retaining the side sections in spaced relation and for forming upper and lower compartments above and below said section, illuminating means in each compartment, sectional lenses

positioned within said open ends, and cover plates secured to the ends of said casing for holding said lenses in place.

4. In a signalling apparatus of the class described, a cylindrical casing having open ends, a series of interlocked partitions within said casing dividing the latter into a plurality of compartments, said partitions consisting of spaced vertically extending sections for forming side compartments outwardly thereof and a central section removably secured to the intermediate portions of said spaced vertical sections for forming upper and lower compartments thereabove and therebelow, a lens positioned within said open ends, illuminating means in each compartment, and cover plates secured to the ends of said casing for holding said lenses in place.

In testimony whereof I affix my signature.
JOHN D. HENDRIX.
